UNITED STATES PATENT OFFICE.

EMANUEL MYETTE, OF PROVIDENCE, RHODE ISLAND.

WIRE-COILING MACHINE.

Application filed June 21, 1923. Serial No. 646,873.

To all whom it may concern:

Be it known that I, EMANUEL MYETTE, a citizen of the United States, residing at Providence, in the county of Providence and State of Rhode Island, have invented new and useful Improvements in Wire-Coiling Machines, of which the following is a specification.

This invention relates to certain new and useful improvements in wire coiling machines, and pertains more particularly to a machine for coiling wire upon a drum or reel. This application is a continuation of, and substitute in part for, an application filed by me on March 15, 1922, Serial No. 543,904.

The primary object of the invention is to provide a machine of this type which has improved means for laying the wire on the reel and for also effecting such laying by guiding of the laying means from the previously laid convolution of the active layer.

A further object of the invention is to provide a machine of the type mentioned which has means for enabling regulation of the speed of guiding means according to the gage of the wire being reeled or coiled.

Another object of the invention is to provide laying means which is capable of laterally and also vertically pivotal movements so as to compensate for any irregularities such as kinks, which may appear in the wire.

A still further object of the invention is to provide novel means for effecting clockwise and counter-clockwise movement of the actuating shaft or means of the wire-layer.

The invention still further aims to provide a machine which is efficient in operation and which will effect the laying or coiling in an expeditious manner.

Still further and other objects will be later set forth and manifested in the course of the following description.

In the drawings:

Figure 1 is a side elevation of the invention;

Figure 2 is a top plan view;

Figure 3 is a fragmentary detail perspective view of the wire laying device.

Figure 4 is a section on line 4—4 of Figure 3;

Figure 5 is a fragmentary detail top plan view of the wire laying device;

Figure 6 is an enlarged sectional detail view showing the laying of the first layer 55 of the wire on the reel;

Figure 7 is a similar view showing the laying of the second layer;

Figure 8 is a top plan view of Figure 6, and

Figure 9 is a top plan view of Figure 7.

In proceeding in accordance with the present invention, a shaft 1 is employed mounted upon uprights 2 and driven by a pulley and belt 3, the shaft 1 having a reel 65 or drum 4 secured thereto so as to rotate therewith.

A sprocket wheel 5 is secured to the shaft 1 and has a chain 6 passing therearound, the chain also passing around a sprocket 70 wheel 7 carried by a shaft 8 the latter journaled in a frame 9. A disk 10 is carried by the shaft 8 and engages with and between a pair of opposed spaced disks 11 and 12, mounted on a shaft 13 carried by the arms 75 14 of a yoke having a hub 15 rotatable on a shaft 16. The yoke is operated by an arm 17 which, as shown in Figure 2, may be formed of an extension of the arm 14, the arm 17 being pivotally connected at 17' 80 to the lower end of a rod 18. The rod 18 is threaded at its upper end through a nut 19 and carries a hand wheel 20 by means of which the rod 18 can be turned and thereby raised or lowered to effect corresponding movement of the shaft 13 by pivotal movement of the yoke hub about the shaft 16.

An indicator rod 21 is provided and which is pivoted to the arm 17, the rod having 85 graduations on its upper end which are readable in conjunction with or in relation to a pointer 22 that is rigidly connected to the frame 9. The graduations indicate the gage of the wire, the yoke being set in accordance with such as will be later more 90 fully set forth.

The disk 11 is fixed to the shaft 13 while the disk 12 is keyed thereon and is held by a spring 23 in resilient engagement with the disk 10.

The shaft 16 carries a sprocket 24 connected by a chain 25 to a sprocket 26, the latter mounted on a clutch member 27 freely rotatable on a shaft 28 journaled at the upper part of the frame 9. A clutch member 29 is also freely rotatable on the shaft 28

- and has a gear 30 thereon, the latter in mesh with a gear 31 mounted on a stub shaft 32.
- The gear 31 is driven by a sprocket 33 mounted thereon and a chain 34, the latter engaged over a sprocket 35 mounted on the shaft 16.
- A clutch 36 is keyed to the shaft 28 to slide thereon and rotate therewith and is disposed between the clutch members 27 and 29. The clutch 36 is freely rotatable in an arm 37 which latter is carried by a rod 38 slidable in the frame 9, and arm 37 being cushioned by a pair of coil springs 39 mounted on the rod 38 and engaging on opposite sides of the arm 37, the springs being engaged at their outer ends by collars 40 fixed to the rod 38. A pair of stops 41 and 42 are carried by the rod 38.
- The wire laying device embodies a main frame or member 43 provided with a threaded socket or nut 44 and an apertured arm 45 the latter freely receiving the rod 38 in its aperture, while the nut 44 threadedly receives the threaded part 45' of the shaft 28. Wire guides 46 having anti-friction wire engaging rollers 47 thereon extend vertically from the frame 43 and are spaced to receive the wire there-between and to guide same to a pair of grooved rollers or wheels 48 carried by the frame 43. A T-shaped pivoting member 50 is pivoted at 51 to frame 43 so as to have vertical movement and pivotally carries the wire laying arm 52 at 53 so that the arm 52 has horizontal pivotal movement. The free outer end of the arm 52 has a fixed upper wire guide 53' slotted to receive the wire, and a pivoted concaved depending guide 54 which receives the convolutions and lies upon the previously laid convolution of the wire, as depicted in Figure 1. The arm of the T-member 50 is horizontally slidable on the pin 51 and is tensioned by cushioning springs 53" encircling the pin 51 and engaging opposite sides of said arm. Shaft 13 drives shaft 16 by chain 55, the latter engaging over sprocket 56 carried by shaft 16 over sprocket 57 carried by shaft 13.
- In operation, the shaft 1 is driven by the belt 3, the shaft in turn driving shaft 8 through the chain 6, and thereby disk 10. The disk 10 through friction drives the disks 11 and 12 and thereby the shaft 13, the latter through chain 55 driving shaft 16. The shaft 16 through chain 34 drives gear 33 and the latter through gears 31 and 30 drives clutch member 29. The shaft 16 through chain 25 drives clutch member 27.
- As the clutch 36 contacts with either the member 27 or 29, the shaft 28 is caused to revolve either clockwise or counter-clockwise, thus effecting corresponding movement of the wire laying device, i. e., first in one direction along the longitudinal axis

of the reel 4 and then in the opposite direction along such axis.

In the movement of the wire laying device in opposite directions along the longitudinal axis of the reel 4 it will be apparent that the guide 54, by virtue of engaging the previously laid wire convolution C of the active layer on the reel, will cause the active layer to be laid according to the previously laid convolution of the active layer. When the arm 45 engages stop 42, shaft 36 will be slid to the left of Figure 2, thereby compressing spring 39 against arm 37, and storing-up power in the spring until the resistance offered by the engagement of clutch member 29 with clutch 36 is overcome and the latter moved by the compressed spring out of engagement with clutch member 29, at which time the power stored up in spring 39 is released and utilized to move clutch 36 into engagement with clutch member 27. Similarly, when arm 45 engages stop 41, the clutch 36 is engaged with the clutch member 29 by corresponding compression of the spring to the left of the arm 37, effecting movement of the arm 52 to the right of Figure 2.

From the foregoing, it will be apparent that the arm 52 is caused to reciprocate along the length of the reel, being guided by the movement of the guide, 54 which responds according to the previously laid convolution of the active layer.

By varying the position of the rod 18 determined by the gage wire being reeled, it will be seen that the yoke and thereby the disks 11 and 12 are caused to vary their relation to the disk 10, so that the speed of movement of the wire laying device is thus increased or decreased according to the diameter of the wire being reeled or laid.

It will be noted that due to the pivotal movement of the guide or shoe 54, and the cushioned movement of the arm 52, any kinks or irregularities in the wire, will not effect the functioning of the arm, since the latter can freely give or respond to such irregularities. The cushioning springs further function to compensate for any disalignment of the heads of the spool 4, so that should such heads be out of true, the arm 52 when reaching its end of travel and contacting therewith will not prevent uniform laying of the wire.

Having thus described my invention, what I claim as new and desire to secure by Letters Patent is:—

1. In a wire coiling machine, a reel, means to rotate the reel, a threaded shaft, a wire laying arm, a guide on the arm to engage the laid convolutions of the wire, a guide on the arm for the wire being laid, a member having threaded engagement with the threaded shaft, means to connect the arm to said member to allow the arm to move verti-

cally and horizontally, a slidable rod having spaced stops arranged to engage opposite sides of the member, spaced clutch members on said shaft, a clutch carried by the rod and operating in the space between the clutch members and engageable with each of the latter, a second shaft, a yoke pivoted on the second shaft and carrying a pair of spaced disks, a disk between and engaged 10 with the pair of disks, means to operate one of the clutch members from the second shaft, means to actuate the second shaft from the pair of disks, means to actuate the other clutch member from the second shaft, and 15 means to adjustably move the yoke about its pivot.

2. In a wire laying machine, wire laying means, rotatable means for actuating the wire laying means, and means to variably 20 actuate the rotatable means including a pair of friction disks, means to pivotally mount one of said disks so as to vary the driving relation thereof to the other disk, and a threaded rotatable member connected to the 25 pivoted means for moving the latter to thereby vary said relation between the disks.

3. In a wire coiling machine, wire laying means, means for actuating the wire laying means, means for operating said actuating 30 means, including driving disks, means to pivotally mount one of said disks, a threaded rod connected to the pivoted means, a nut through which the rod operates, and a gage rod connected to the pivotal means and 35 having a pointer associated therewith for enabling setting of the disk according to the gage of wire being laid.

4. In a wire coiling machine, wire laying means, means to actuate the wire laying 40 means including a variable drive having a pair of disks, a pivoted yoke carrying one of the disks and having an arm, a threaded shaft pivoted to the arm, and a nut through which the shaft operates to raise or lower 45 the arm and thereby vary the relation of said disk to the other disk.

5. In a wire coiling machine, a reel, means to rotate the reel, wire laying means including means formed to engage on top of the 50 previously laid convolution so as to be guided thereby and formed to guidingly engage the wire being laid so as to effect laying of the active layer in accordance with the previously laid convolution of the active 55 layer, and means to actuate the wire laying means.

6. In a wire coiling machine, a reel, means to rotate the reel, wire laying means including a lower guide formed to engage on top 60 of the previously laid convolutions of the active layer of the wire, an upper guide engaging the wire to effect laying of the active layer in accordance with the previously laid convolution of the active layer, and means 65 to actuate the wire laying means.

7. In a wire coiling machine, a reel, means to rotate the reel, wire laying means including a reciprocable member, a wire laying arm, means to pivotally connect the arm to the member to allow the arm to move vertically and horizontally, means to reciprocate the arm, means carried by the arm and resting upon the previously laid convolution of the active layer and engaging said convolution of the wire to be guided thereby, and 70 means carried by the arm and engaging the wire being laid to effect laying of the active layer in accordance with the previously laid convolution of the active layer.

8. In a wire coiling machine, a reel, means to rotate the reel, wire laying means guidingly resting upon the previously laid convolution of the active layer and movably supported thereby and being engaged with the wire being laid to effect laying of the 85 active layer in accordance with the previously laid convolution of the active layer, and means to actuate the wire laying means.

9. In a wire coiling machine, a reel, means to rotate the reel, wire laying means engaged with the previously laid convolution of the wire and with the wire being laid to effect laying of the active layer in accordance with the previously laid convolution of the active layer, and means to actuate 90 the wire laying means.

10. In a wire coiling machine, a reel, means to rotate the reel, wire laying means engaged with the previously laid convolution of the wire so as to be moved thereby 100 axially of the reel and engaged with the wire being laid to move the latter axially of the reel to effect laying of the active layer in accordance with the previously laid convolution of the active layer, and means to 105 actuate the wire laying means.

11. In a wire coiling machine, wire laying means, means to actuate the wire laying means including a variable drive having a 110 pair of friction disks, means to pivotally support one of the disks, means to adjustably hold said disk supporting means in position, and gage means pivotally carried by the disk supporting means and movable therewith.

12. In a wire coiling machine, wire laying means, means to actuate the wire laying means including a variable drive having a pair of friction disks, a member pivoted between its ends and carrying one of the disks at one end, means connected to the other end of the member to adjustably hold said member in position, a gage rod pivoted to the last named end of the member and a stationary pointer member guidingly engaged with the gage rod.

13. In a wire coiling machine, a reel, means to rotate the reel, a wire laying device, a threaded shaft for actuating the wire laying device, a spaced clutch members on 130

- the shaft, a slidable rod having a clutch operating in the space between the clutch members, means actuated by the wire laying device to reciprocate the rod, a second shaft, a member pivoted on the second shaft, and having a friction disk thereon, a second friction disk engaged with the first named disk, means to drive the second disk from the reel rotating means, means to operate one of the clutch members from the second shaft, means to actuate the second shaft, from the first named disk, means to actuate the other clutch member from the second shaft, and means to adjustably move the pivoted member.
14. In a wire coiling machine, a reel, means to rotate the reel, wire laying means including an arm, a T-shaped member, a horizontal pin pivotally and slidably supporting the arm of said T-member, coil springs mounted on the pin and engaging opposite sides of the arm of the T-member, a vertical pin pivotally connecting the wire laying arm to the T-member, an upper guide on the wire laying arm, and a pivoted wire
- engaging shoe carried by the wire laying arm.
15. In a wire coiling machine, a reel, means to rotate the reel, wire laying means including a vertically and horizontally pivoted arm, means to horizontally cushion the arm and a pair of wire guides on the arm one of which is pivoted.
16. In a wire coiling machine, a reel, means to rotate the reel and wire laying means including a cushioned and universally movable wire laying arm.
17. In a wire coiling machine, a reel, means to rotate the reel, and wire laying means including a cushioned and universally movable wire laying arm, having a pivoted wire guide.
- In testimony whereof I have signed my name to this specification in the presence of two subscribing witnesses.

EMANUEL MYETTE.
